For himself

UNITED STATES PATENT OFFICE.

J. B. SARGENT, OF NEW BRITAIN, CONNECTICUT.

DESIGN FOR A COAT AND HAT HOOK.

Specification forming part of Design No. 1,560, dated April 1, 1862.

To all whom it may concern:

Be it known that I, J. B. SARGENT, of New Britain, in the county of Hartford and State of Connecticut, have produced a new and Improved Design for a Coat and Hat Hook; and I do hereby declare that the following is a full, clear, and exact description of the same, reference being had to the accompanying drawings, forming a part of this specification, in which—

Figure 1 represents a side elevation of my coat and hat hook. Fig. 2 is a sectional front elevation of the same. Fig. 3 is a perspective view of the same.

Similar letters of reference in the three views indicate corresponding parts.

My design consists of a bracket representing an oak leaf or another leaf of a similar shape, and from said bracket two arms extend, one in a horizontal and the other in an upward-inclined direction, each representing a branch of a tree.

To enable others skilled in the art to fully understand and use my invention, I will proceed to describe it with reference to the drawings.

The bracket which serves to secure the hook to the wall, and which is provided with two holes *a* to receive screws for the purpose of fastening it, is ornamented by a leaf *A*, resembling an oak leaf or any other leaf of

a similar shape. The two halves of this leaf incline toward both sides from the central rib *b*, and secondary ribs *c* extend from said central rib toward both sides, thus giving to the said leaf a natural appearance. From the leaf *A* two arms *B* extend, one in an inclined-upward direction and the other in a nearly horizontal direction, as clearly shown in Fig. 1. These arms have the appearance of the branches of a tree. They become gradually thinner toward their outer ends, and their surfaces are made to resemble the bark of a tree. From the branch *B* three sprigs *d* extend in various directions and at variable intervals, similar to the sprigs of a natural branch, and two sprigs *e* similar to the sprigs *d* extend from the branch *C*. The branches and sprigs correspond in their appearance to the bracket, and serve to give to the whole a handsome finish.

What I claim as new, and desire to secure by Letters Patent, is—

A new design for a coat and hat hook having its bracket ornamented by a leaf *A*, as described; and I also claim the branches *B* *C* with sprigs *d* *e*, as specified.

J. B. SARGENT.
